E. ALSCHULER

BATTERY HANDLAMP.

Filed Jan. 4, 1919

Inventor:
ERNEST ALSCHULER,
John N. Bruninga,
his Attorney.

UNITED STATES PATENT OFFICE.

ERNEST ALSCHULER, OF ST. LOUIS, MISSOURI, ASSIGNOR TO UNITED STATES ELECTRIC MANUFACTURING CORPORATION, OF NEW YORK, N. Y., A CORPORATION OF NEW YORK.

BATTERY HANDLAMP.

Application filed January 4, 1919. Serial No. 269,704.

To all whom it may concern:

Be it known that I, ERNEST ALSCHULER, a citizen of the United States, and residing at St. Louis, Missouri, have invented the new and useful Improvement in Battery Handlamps, of which the following is a specification.

This invention relates to battery hand lamps.

- 10 In a battery hand lamp having a metallic battery-receiving casing, difficulty is experienced in providing a simple construction whereby the circuit may be closed through the lamp and battery.
- 15 One of the objects of this invention, therefore, is to provide a battery hand lamp having a metallic battery-receiving casing, which is so constructed and arranged as to permit simple but substantial connections 20 to be made which are not liable to short circuit.

In a battery hand lamp, the lamp itself is usually mounted in a base which forms the reflector and the battery terminal engages directly with one of the terminals (usually the central terminal) of the lamp. With such a construction when the hand lamp is subjected to shocks, as when it is allowed to drop, the impact will frequently 30 cause breakage of the lamp filament.

Another object of this invention, therefore, is to provide a yielding contact between the battery and the lamp terminals which will act as a shock absorber and thereby prevent breakage of the lamp filament, which is adapted for application to any standard form of hand lamp.

Another object is to provide a hand lamp having a novel switching arrangement 40 which is simple in construction, effective in its action and cheap to manufacture.

Further objects will appear from the detail description, taken in connection with the accompanying drawing, in which:

45 Figure 1 is a longitudinal section of a battery hand lamp embodying this invention;

Figure 2 is an enlarged detail of Figure 1, showing the contact ring and its connection;

Figure 3 is a section on the line 3—3, Figure 1, showing the switch;

Figure 4 is a section on the line 4—4, Figure 3;

Figure 5 is an enlarged detail of Figure 55 1, showing the shock absorber;

Figure 6 is a view similar to Figure 5, but showing another embodiment of this invention; and

Figure 7 is a view similar to Figure 4, 60 showing still another embodiment.

Referring to the accompanying drawing, and more especially to Figures 1, 2 and 3, 1 designates a casing of metal having enlarged threaded ends 2 and 3, which are 65 adapted to receive threaded rings 4 and 5 respectively. The ring 4 has a closed end 6, carrying a spring 7 adapted to bear against and make contact with the end terminal of a battery 8 carried by the casing, it being understood that there are two or more batteries arranged end to end in a single covering or carton of paper or other light insulating material.

Arranged at one end of the casing is a 75 reflector 9 which has a threaded thimble 10, adapted to receive the metallic terminal 11 of a lamp 12. This reflector has a flange 13, adapted to engage and make contact with a metallic ring 14 spaced from 80 the end 3 by a ring 15 of insulating material. The rings 14 and 15 are threaded to correspond with the threaded end 3, so that the rings are arranged in nested relation within the end 3 of the casing, but whereby 85 the contact ring 14 is insulated from the casing. The insulating ring 15 is preferably provided with an end flange 16 to form a stop and also insulate the end 3 90 of the casing.

Mounted on the flange 13 of the reflector is a lens 17 which is retained in place by a flange 18 of the ring 5. The reflector flange 13 is of a smaller diameter than the ring 5 so that it will not contact with the ring, 95 and the reflector body makes a snug fit with the contact ring 14, this contact ring being preferably split as shown in Figure 2 so as to make a firm mechanical connection with the insulating ring 15 in 100 order that the contact ring may be firmly retained in position.

Mounted inside of the casing is a base 19 of insulating material, which is secured to the casing in any suitable manner as by 105 rivets 20. This base carries a contact 21 connected by an insulated lead 22 with the contact ring 14. The contact 21 is positioned in

an enlarged aperture 23 formed in the casing so that this contact will be insulated from the casing. Mounted on the outside of the casing in any suitable manner is a base for 5 a circuit-closing switch which may be formed of sheet metal, and has a struck-up portion forming a housing 24 for the switch elements. One of these elements has the form of a flat spring and carries at one extremity an operating button 26 and a contact 25 adapted upon flexure of the switch member by means of the button 26 to contact with the head of the rivet 21. The second switch member is mounted underneath 10 the first and secured in position by overlapping flanges extending inwardly from a manipulative member 28 mounted outside of the housing 24. These flanges extend through slots in the housing 24, embrace the edges of the first switch member and, passing 15 through notches in the sides of the second switch member, are folded over underneath said second member to secure it in position. This construction is clearly shown in Figures 20 3 and 4. The second switch member is provided with a curved contacting terminal 27 which is adapted to make contact with the head of the rivet 21 when this member is slid forward along the housing 24 by movement 25 of the manipulative member 28. It will be seen that this provides two ways of closing the circuit. Momentary contact may be made by pressing the button 26 so as to bring the contact 25 into engagement with the rivet 21, or the member 28 may be moved forward carrying with it the contact 27 into engagement with the rivet 21 for the same purpose.

When either of the contacts 25 or 27 is 40 moved into engagement with the contact 21, the circuit will be closed through the contact on the casing, the contact 21, the lead 22, the contact ring 14, the reflector 9, the lamp terminal 11, the lamp filament, the lamp terminal 30, the battery 8, the spring 7, the cap 6 and the casing 2. It will be noted that the reflector, forming the lamp carrying base, is insulated from the metal casing and that this is obtained in a simple and effective manner through the provision of the contact ring insulated from the end of the casing by the simple insulating ring. This not only furnishes a simple and effective structure, but also prevents short circuiting 45 of the lamp by extraneous connections, for the reason that the circuit can only be closed by movement of the switch. It will be seen, therefore, that with this construction, it is possible to obtain in a metal casing structure 50 either a duration or flash contact, the former being obtained by movement of the thumb piece 28 and the latter by movement of the button 26.

Referring to Figures 1 and 5, the threaded nipple 10 has mounted thereon a base pro-

vided with means for connecting the central lamp terminal 30 with the battery terminal 29. This base comprises a disc 31 of insulating material, which is internally threaded to take over the nipple 10 and which carries a casing 32 of metal having a flange portion 33 crimped over the disc. When this base is screwed onto the nipple 10 on the reflector, its bottom 34 will make contact with the terminal 29 of the battery. Mounted in the bottom of this base is a spring 35 carrying a metal follower 36, adapted to make contact with the terminal 30 of the battery. The electrical connection is, therefore, made through the bottom 34, the spring 35 and the follower 36. With this construction there is a yielding contact connection from the battery to the lamp terminal. It will further be noted that the support 32 being mounted on and insulated from the reflector, all shocks will be absorbed by the reflector while such shocks will not be transmitted to the central lamp terminal on account of the yielding contact connection which absorbs the shock.

In the construction shown in Figure 6, the yielding element comprises a plate 38 retained in the bottom 34 of the support 32 by the crimped portion 37, and this plate has a tongue 39 struck up therefrom and adapted to bear against the lamp terminal 30. It will be understood, of course, that the plate 38 is of spring metal so that the tongue 39 will yieldingly bear against the lamp terminal and thus absorb all shocks and jars.

In the construction shown in Figure 7, the insulating disc 31 has secured thereto by rivets 40 or otherwise, a frame or stirrup 41 of spring metal providing a cross piece 42, adapted to contact with the terminal 29 of the battery and provided with one or more struck up portions 43 which are adapted to bear against the lamp terminal 30.

This finger or these fingers is or are each attached at one end only, while the other end is free, and where two fingers are used, they extend in opposite directions. These fingers, therefore, bear yieldingly against the lamp terminal so as to absorb and cushion all shocks and jars.

It will be noted that the casing or bumper is a metallic one, and not only engages but also makes contact with the battery terminal, while the yielding contact engaging the lamp terminal has a direct electrical connection with the bumper and, therefore, with the battery terminal so as to provide a permanent connection between the battery and the lamp. In accordance with this invention, therefore, a shock absorber is provided which can be applied to any standard form of hand lamp or flash light for by the simple removal of the reflector, this shock absorber can be applied to the nipple thereof, and

when in position, not only provides a bumper for the battery in order to take the shocks but also provides a contact between the battery and the lamp to absorb the 5 shocks.

It is obvious that various changes may be made in the details of construction without departing from the spirit of this invention; it is, therefore, to be understood that this invention is not to be limited to the specific 10 construction shown and described.

Having thus described the invention, what is claimed is:

1. A battery hand lamp, comprising, a 15 metal battery-receiving casing adapted to form a part of the lighting circuit, a lamp-carrying reflector fixed in the end of but insulated from said casing, a circuit-closing switch mounted on said casing, and a fixed 20 connection from said reflector to said switch.

2. A battery hand lamp, comprising, a metal battery-receiving casing adapted to form a part of the lighting circuit, a lamp-carrying base fixed therein insulated from 25 said casing, a circuit-closing switch mounted on, but having one of its contacts insulated from, said casing, and a fixed connection from said base to said contact.

3. A battery hand lamp having a metal 30 battery-receiving casing adapted to form part of the lighting circuit, a lamp-carrying base fixed therein, a lens, and a circuit-closing switch mounted thereon, characterized by the feature that a contact element, connected with said switch and engaged by said 35 base adjacent the lens, is insulated from the casing.

4. A battery hand lamp having a metal 40 battery-receiving casing adapted to form part of the lighting circuit, a lamp-carrying base fixed therein, a lens, and a circuit-closing switch mounted thereon, characterized by the feature that a base-contacting and 45 positioning ring, connected with said switch, and adapted to engage the base adjacent the lens, is insulated from said casing.

5. A battery hand lamp having a metal 50 battery-receiving casing adapted to form part of the lighting circuit, a lamp-carrying base fixed therein, a lens, and a circuit-closing switch mounted thereon, characterized by the feature that a base contacting ring, connected with said switch, and adapted to 55 engage the base adjacent the lens, is separated from the casing by an insulating and positioning ring.

6. A battery hand lamp having a metal 60 battery-receiving casing, a flanged reflector and a circuit-closing switch, characterized by the feature that the end of the casing has a contact ring insulated from the casing to be engaged by said flange.

7. A battery hand lamp having a metal 65 battery-receiving casing, adapted to form a part of the lighting circuit, a flanged re-

flector fixed therein, and a circuit-closing switch mounted thereon, characterized by the feature that the end of the casing has a contact ring spaced from the casing by an insulating ring and adapted to position and 70 contact with the flanged end of said reflector.

8. A battery hand lamp having a metal 75 battery-receiving casing adapted to form a part of the lighting circuit and a lens, characterized by the feature that a contact ring adjacent the lens and forming part of the lighting circuit is spaced from the casing by an insulating ring.

9. A battery hand lamp having a metal 80 battery-receiving casing, with a threaded end adapted to form a part of the lighting circuit, characterized by the feature that a threaded contact ring is spaced from the casing 85 by an interposed insulating ring.

10. A battery hand lamp, comprising, a metal battery-receiving casing, a lamp-carrying base insulated from said casing, a circuit-closing switch mounted on, but having one of its contacts insulated from, said 90 casing, and a connection from said base to said contact, said switch having a plurality of contacts cooperating with said first contact.

11. A battery hand lamp, comprising, a metal battery-receiving casing, a lamp-carrying base insulated from said casing, a circuit-closing switch mounted on, but having one of its contacts insulated from, said 95 casing, and a connection from said base to said contact, said switch having a plurality of 100 contacts, adapted to make intermittent or duration contact with said first contact.

12. In a battery hand lamp having a battery-receiving casing a battery and a reflector provided with a nipple adapted to receive a lamp, a shock absorbing device adapted for mounting on the nipple, said device having a metallic bumper for engaging and contacting with the battery terminal and having directly connected therewith 105 a yielding contact for engaging the lamp 110 terminal.

13. In a battery hand lamp having a battery-receiving casing a battery and a reflector provided with a nipple adapted to receive a lamp, a shock absorbing device having, an insulating element adapted for mounting on the nipple, and a metallic bumper for engaging and contacting with the battery terminal and having directly 115 connected therewith a yielding contact for 120 engaging the lamp terminal.

14. In a battery hand lamp having a battery-receiving casing a battery and a reflector provided with a nipple adapted to receive a lamp, a shock absorbing device having, an insulating element adapted for mounting on the nipple, a metallic casing on 125 said element for engaging and contacting with the battery terminal, and a yielding con- 130

tact directly connected with said casing and adapted to engage the lamp terminal.

15. In a battery hand lamp having a battery-receiving casing a battery and a reflector provided with a nipple adapted to receive a lamp, a shock absorbing device, comprising, an insulating element adapted for mounting on the nipple, a metallic casing on

said element for engaging and contacting with the battery terminal and a yielding contact mounted within and directly connected with said casing and adapted to engage the lamp terminal. 10

In testimony whereof I affix my signature this 12th day of November, 1918.

ERNEST ALSCHULER.
